ATTORNEY

UNITED STATES PATENT OFFICE.

ROMILDO CASCIANI, OF TRENTON, NEW JERSEY.

DESIGN FOR A COMBINATION TRAY AND CONDIMENT HOLDER.

Application filed December 6, 1922. Serial No. 4,513. Term of patent 7 years.

To all whom it may concern:

Be it known that I, ROMILDO CASCIANI, a citizen of the United States, residing at Trenton, in the county of Mercer and State of New Jersey, have invented a new, original, and ornamental Design for Combination Tray and Condiment Holder, of which the following is a specification, reference being had to the accompanying drawing, forming part thereof.

The figure is a perspective view of the combination tray and condiment holder.

I claim:

The ornamental design for a combination tray and condiment holder, as shown.

ROMILDO CASCIANI.
